CLAIM

The ornamental design for a display screen with graphical user interface, as shown and described.

DESCRIPTION

FIG. 1 is a front view of a display screen with graphical user interface showing a first embodiment of our new design thereof; and,

FIG. 2 is a front view of a display screen with graphical user interface showing a second embodiment of our new design. The uneven-length broken lines are imaginary lines not found on the display screen with graphical user interface that represent unclaimed boundaries of the claimed design. The even-length broken lines showing other aspects of the display screen with graphical user interface are for environmental purposes only and form no part of the claimed design.
